UNITED STATES PATENT OFFICE.

CLARENCE HEISEY, OF NEWARK, OHIO, ASSIGNOR TO A. H. HEISEY & CO., OF NEWARK, OHIO.

DESIGN FOR A JAR OR BOTTLE.

46,864.

Specification for Design.

Patented Jan. 19, 1915.

Application filed August 18, 1914. Serial No. 857,411. Term of patent 7 years.

To all whom it may concern:

Be it known that I, CLARENCE HEISEY, a citizen of the United States, residing at Newark, Ohio, have invented a new, original, and ornamental Design for a Jar or Bottle, of which the following is a specification, reference being had to the accompanying drawing, forming part thereof.

The drawing is a side elevation of a jar or bottle embodying my invention.

I claim:—

The ornamental design for a jar or bottle, substantially as shown.

CLARENCE HEISEY.

Witnesses:

MAX B. NORPELL,
MAUD BOTT.
